UNITED STATES PATENT OFFICE.

DAVID C. HALE, JR., OF CINCINNATI, OHIO.

PROCESS OF PRESSING GARMENTS.

1,038,123.

Specification of Letters Patent.

Patented Sept. 10, 1912.

Original application filed August 16, 1911, Serial No. 644,430. Divided and this application filed January 10, 1912, Serial No. 670,397.

To all whom it may concern:

Be it known that I, DAVID C. HALE, Jr., a citizen of the United States, residing at Cincinnati, in the county of Hamilton and State of Ohio, have invented certain new and useful Improvements in Processes of Pressing Garments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a process of pressing garments by means of heated air under compression, and comprises subject-matter which is divided from my co-pending application, Serial Number 644,430, filed Aug. 16, 1911.

The heated air is applied to the garment while between the pressing surfaces and while the pressing surfaces are acting thereon. Heretofore it has been the custom to apply steam to garments in the operation of pressing the same. This is objectionable for several reasons, principally because it imparts excessive moisture to the garment with the result that the garment retains the creases but a comparatively short time after pressing, and requires frequent repressing. And further, the repeated application of steam to textile fabrics impairs the life thereof, and is undesirable for this reason, as well as for the reason that the creases in the garment last for but a comparatively short time. And further, steam has the effect of taking the finish off the lining of the garment, making it necessary to run a hot iron over the lining to restore the gloss or finish which is thus destroyed.

It is therefore, the object of my invention to provide a method of pressing garments in a manner that enables the pressing operation to take place under conditions of dryness, and whereby the creases imparted to the garment are of a more lasting nature.

The action of the heated air under compression is such that the garment is maintained between the pressing surfaces free from wrinkles, during the pressing operation. In pressing a fabric, it is necessary that it be given a certain limpness without

moisture. Heated air under compression has been found to impart to the garment this condition without impregnating it with moisture. The steam or moisture usually imparted to garments in the pressing operation causes the garment to shrink more or less. In applying heated air to the surface of the garment, it is unnecessary to apply any other source of heat. The liability of scorching the garment or imparting a shining surface to the pressed garment is avoided. And again, in the use of heated air, the heat is uniformly distributed throughout the pressing members instantaneously and the work of pressing is done expeditiously as well as efficiently.

I am aware that heretofore, air has been used in laundry work for drying steam soaked pads, and that hot air has been used in such work for drying collars and cuffs after they have been ironed from a damp state. But both of these methods necessarily employ in the first place, excessive moisture, as any machine must do in laundrying linen or washed goods. Such, however, is not my process, which may be properly termed a dry process, as compared with any that wets the goods by steam or water preparatory to pressing or ironing.

In the following specification and in the drawings, similar reference characters refer to the same parts.

Referring to the accompanying drawings, Figure 1 is an elevation of a machine by means of which my process may be carried out. The table, the inclosing base, and the air heater are shown in section. The air compressor is also shown. Fig. 2 is a sectional view of the upper pressing member, into which the heated air under compression is discharged.

Referring more particularly to the drawings, 1 designates a base or casing containing an air compressor 2 and an air storage and heating cylinder 3, to which the air is delivered from the compressor 2 through a pipe 4. A suitable means for heating the air in the cylinder 3 consists of electrical resistance coils, as shown on the interior of said cylinder in Fig. 1. The base 1 has a table 5, above which are mounted the pressing members consisting of the buck 6 and the movable presser head 7. Between these two members the garment to be pressed is

placed. Any of the well known mechanical means for operating the presser head 7 may be employed or this may be done by hand. It is therefore not deemed necessary to show 5 any of the mechanical details for this purpose, as they do not enter into the invention. Forming a communication between the hot air storage tank 3 and the presser head 7 is a pipe 10. This pipe is suitably connected 10 with a pipe 9 which is controlled by a valve and is connected with an air distributing pipe 8 in the interior of the presser head 7. The bottom surface of the head 7 consists 15 of the necessary layers of fabric 11 through which the air is forced in contact with the garment lying between the pressing surfaces. When the garment is engaged between the presser head 7 and the buck 6, the heated compressed air is applied thereto. 20 The first effect is to heat the presser head and smoothen and straighten out the garment and free it from wrinkles. The admission of the heated air to the presser head continues during the pressing operation and 25 maintains a uniform heat. The minute jets from the distributing pipe 8 effectually deliver the air to all the surface of the garment inclosed between the pressing members, and the result is the garment is pressed

while in a condition of limpness and free 30 from moisture.

Briefly the process is as follows: The pressing surfaces are separated sufficiently to enable the garment to be placed upon the buck 6. The hot air is admitted to the 35 presser head 7 and has the effect of heating the presser head and freeing the garment from wrinkles before the presser head is brought into contact therewith, and to impart to the garment the necessary limpness 40 which continues after the pressing members are brought together and until the operation is completed.

Having described my invention, I claim:

The herein described process of pressing 45 garments, which consists in placing the garment to be pressed between pressing surfaces and in applying heated air under compression to said garment while said garment is under pressure between the pressing surfaces and until the operation of pressing 50 said garment is completed.

In testimony whereof I affix my signature, in presence of two witnesses.

DAVID C. HALE, JR.
